CHARGING HOPPER AND DOOR MECHANISM FOR ROTARY-DRUM MIXERS

Lawrence E. Joseph, Fox Chapel Borough, Allegheny County, Pa., assignor to Blaw-Knox Company, Pittsburgh, Pa., a corporation of New Jersey

Application April 8, 1946, Serial No. 660,359

7 Claims. (Cl. 259—161)

1 This invention relates to apparatus for charging materials, such as cement, sand and aggregate, into the open end of a rotary mixer drum and closing said end while the materials are being mixed by rotation of the drum. The invention is particularly adapted to and will be specifically described with reference to so-called high-discharge concrete mixers which are usually truck mounted, but is also applicable to other kinds of mixers embodying a rotating drum.

High-discharge mixers as constructed heretofore have usually been provided with a charging hopper permanently mounted adjacent the open end of the drum and having sliding contact therewith so the hopper can be held stationary while the drum rotates. This construction requires means for sealing the joint between the hopper and drum. Such sealing means have a relative short life and are troublesome to maintain. Ordinarily no closure is provided for the open end of the drum but a temporary cover is sometimes applied while the truck is traveling. If the drum is not provided with a charging hopper, the mixer must be backed up under a stationary hopper supported below the supply of materials. This is obviously a slow operation requiring careful maneuvering of the truck.

I have invented a novel charging hopper and door mechanism for a rotary mixer drum which overcomes the aforementioned disadvantages, permitting various materials to be introduced readily and in rapid succession, and providing a tight closure for the open end of the drum without sliding contact between the closure and drum. In a preferred embodiment, I provide supports extending outwardly from the frame in which the mixer drum is journaled for rotation, and mount a charging hopper on said supports for movement from and toward the open end of the drum. I also provide a closure movable from a position overlying the end of the drum to an out-of-the-way position to permit the hopper to be moved into charging relation to the drum. In one form of the invention, the closure is mounted on the hopper and both are rotatable as a unit between alternative positions, in addition to being movable from and toward the drum. In another form, the closure is pivoted for angular movement relative to the hopper.

A complete understanding of the invention may be obtained from the following detailed description and explanation which refer to the accompanying drawings illustrating two preferred embodiments. In the drawings,

Figure 1 is a partial side elevation of the charging end of a mixer having the invention applied

2 thereto with a portion broken out and shown in section;

Figure 2 is a similar view showing the hopper and door retracted, with a different portion broken out and shown in section;

Figure 3 is a view similar to Figure 2 showing the hopper in charging relation to the drum;

Figure 4 is a section taken along the plane of line IV—IV of Figure 1;

Figure 5 is a partial transverse section taken along the plane of line V—V of Figure 1;

Figure 6 is a view similar to Figure 1 showing a modification;

Figure 7 is a view of the modified form similar to Figure 3;

Figure 8 is a section taken along the plane of line VIII—VIII of Figure 6; and

Figure 9 is a partial transverse section taken along the plane of line IX—IX of Figure 6.

Referring now in detail to the drawings and, for the present, to Figures 1 through 5, a mixer drum 10 is journaled for rotation in a supporting frame 11 with its axis inclined upwardly. The frame 11 may be mounted on a truck chassis and suitable means are provided for rotating the drum to effect the mixing of material charged into the drum. Fixed blades are mounted internally of the drum to assist the mixing action. A circular charging and discharging opening 12 at the upper end of the drum has a flange or lip 13 extending therearound. The blades are arranged in the drum so that on reversal of the latter, the contents of the drum are forced upwardly and outwardly through the open end.

A yoke 14 extends outwardly from the frame 11 in the plane through the axis of the drum. The yoke includes parallel side portions 15 secured to the sides of an arch 16 extending upwardly around the end of the drum. The frame 11 and the yoke 14 are fabricated from suitable structural shapes, the yoke being secured to the arch 16 by gusset plates 17. Diagonal braces 18 extending from the frame to the yoke impart the desired rigidity to the entire supporting structure.

A charging hopper 19 in the form of a tubular elbow fabricated from plate is disposed between the side portions 15 of the yoke 14. Trunnions 20 are secured to the hopper on opposite sides and extend therefrom along a common transverse axis. The trunnions are journaled in bearing blocks 21 and extend through slots 22 in the side portions 15. The blocks 21 are slidable in slots extending longitudinally of guide bars 23 secured to the side portions 15. Double-acting hydraulic motors 24 are trunnioned in the side portions 15 of the yoke and outer bearing plates 25

extending therefrom. The piston rods of the motors are secured to collars 26 fitting on the extreme ends of the trunnions 20. The hydraulic motors are supplied with fluid under pressure from any convenient source, under the control of a single manually operable valve (not shown). The valve is adapted to actuate both the motors simultaneously in the same direction, whereby they act in unison to move the hopper away from the end 12 of the drum to the position shown in Figure 2 or return it to the position shown in Figure 1.

A closure or door 27 in the form of a dished circular plate is mounted on the hopper for engagement with the lip 13. The hopper has spaced circumferential angles 28 secured thereto and a bearing block 29 is secured centrally theretwix by bolts 30. A bearing plug 31 is journaled in a bore through the block 29 and has its exposed face concave. A bearing boss 32 in the form of a spherical segment is secured centrally of the closure 27 and is yieldingly held against the exposed face of the plug 31 by a through pin 33 having a compression spring thereon. The end of the pin 33 on the inside of the closure and the compression spring are enclosed within a cylindrical housing having a removable cover 34. As clearly shown in Figure 4, the pin extends through a central hole in the plug 31 and through a larger central hole in the boss 32. By this construction, the closure is universally supported on the hopper for limited tilting movement in any direction. It is thus self-aligning and self-centering so that it automatically seats itself properly against the lip 13 when the hopper is moved to the position shown in Figure 1.

In addition, the closure is rotatable about its axis with the drum 10 by virtue of the fact that the plug 31 is journaled in the block 29. The closure may thus be designed to fit tightly against the lip 13 since there is no continued sliding movement therebetween.

When the hopper and closure have been retracted from the position shown in Figure 1 to the position shown in Figure 2, the contents of the drum may be discharged, as previously stated, by reversing the direction of rotation thereof. The concrete, for example, after being mixed by rotation of the drum, is thus caused to flow upwardly along the interior of the drum, out through the open end and down over the lip 13. A guide chute or spout 35 supported on the frame 11 delivers the outwardly flowing concrete into a receptacle positioned thereunder or to any point of delivery accessible to a truck.

In order to place the hopper into charging position relative to the drum, it must first be rotated counterclockwise through an angle of about 120° from that in which it is shown in Figure 2 and then advanced to the position shown in Figure 3. For the purpose of rotating the hopper, one of the trunnions 20 has a gear 36 keyed thereto as shown in Figure 5. The gear is turned by means of a pinion 37 keyed to a hollow shaft 38 having a hand wheel 39 keyed thereto. The shaft 38 turns in a bearing sleeve 40. The sleeve 40 extends outwardly from a post 41 extending upwardly from one of the bearing blocks 21.

A disc 42 secured to the trunnion 20 adjacent the gear 36 has holes spaced circumferentially thereof adapted to accommodate a locking pin 43, the holes being so positioned as to align with the pin in extreme positions of the hopper, i. e., those shown in Figures 2 and 3. The pin 43 is

slidable in an axial bore through the shaft 38 and is normally urged into locking position by a compression spring 44 positioned within an enlargement of the bore at the outer end of the shaft.

The pin 43 has a knob 45 at the outer end thereof whereby the rod may be retracted when it is desired to rotate the hopper. The hub 46 of the hand wheel confines the spring and locking pin within the bore through the shaft 38.

For the sake of completeness, a full operating cycle including charging, mixing and discharging stages will now be described. Assuming that the drum 10 has a charge of material therein to be mixed and the hopper and door are in the positions shown in Figure 1, mixing may be effected by turning the drum in the proper direction. During the mixing operation, the closure 27 turns with the drum and maintains tight-fitting engagement therewith to prevent leakage of the mixer contents. When the desired mixing period has elapsed, the drum 10 is stopped and the motors 24 are operated to retract the hopper and closure to the positions shown in Figure 2. Reverse rotation of the drum will then cause concrete to be discharged from the end of the drum over the lip 13 through spout 35 as indicated by the arrow. When the mixer contents have been discharged, the drum is stopped and another batch of material may be charged thereto by pulling out on the knob 45 of locking pin 43 and turning hand wheel 39 to bring the hopper into charging position. The motors 24 are then operated to cause the discharge end of the chute to enter the open end of the drum as shown in Figure 3. The chute is then ready to receive material for delivery into the drum as shown by the arrow. It will be evident that, since the door or closure 27 is mounted on the hopper, it automatically swings to an out-of-the-way position as the hopper is rotated into material-receiving position.

After the succeeding batch of material has been charged into the drum, the motors 24 are then actuated to retract the hopper and the latter is rotated back to its original position, thus bringing the door into axial alignment with the drum. The door is brought into tight-sealing engagement with the drum by operating the motors to move the hopper toward the drum. The locking pin 43 automatically enters one of the holes in the disc 42 when the hopper comes to either extreme of its angular movement and thereafter maintains the hopper against rotation until the pin is again withdrawn.

Figures 6 through 9 illustrate a modified form of construction generally similar to that described above. Various elements of the modified construction are designated by the same numerals used in describing the structure of Figures 1 through 5, with a prime affixed thereto. The principal difference between the construction already described and that illustrated in Figures 6 through 9 is that the hopper 19' of the latter does not rotate about a transverse axis and the closure 27' is mounted independently of the hopper for swinging movement from a position overlying the end of the drum 10 to an out-of-the-way position.

The trunnions or more properly the stub shafts 29' of the hopper 19' are keyed to the bearing blocks 21' and are thus held against rotation. The hopper is movable rectilinearly, however, from the position shown in Figure 6 to the position shown in Figure 7 by means of the motors 24'. The piston rods of the motors are secured

to links 49 extending forwardly from the bearing blocks 21'. The door or closure 27' is rotatably mounted on a yoke 50 in the same manner as the door 27 is rotatably mounted on the hopper 19. The yoke 50 is journaled on the shafts 20'. Gear 36' is secured to the yoke 50 for causing angular movement thereof to swing the door from closed position to out-of-the-way position. It will be understood that slight retraction of the blocks 21' will be necessary to permit the door to clear the lip 13 before the yoke can be swung about the shafts 20'. When the door has been swung to an out-of-the-way position, as indicated in Figure 7, the hopper 19' may be advanced by the motors 24' into charging relation to the drum 10. The door 27', of course, moves rectilinearly with the hopper but is angularly movable independent of the hopper.

As shown in Figure 9, the mechanism for rotating the yoke 50 is substantially the same as that shown in Figure 5, the only difference being that the disc 42' having holes cooperating with the locking pin 43' is secured to the yoke 50 for angular movement therewith, instead of to the hopper.

It will be apparent from the foregoing that the invention is characterized by numerous advantages over means available heretofore for charging batches of material into a mixer. In the first place, the hopper is mounted on the frame which supports the drum for rotation and may easily be placed in operative relation thereto. Secondly, a tight-fitting closure is provided for the open end of the drum and rotatable therewith so that sliding contact and the necessity for sealing are eliminated. In addition, the door is self-centering. In the form of the invention first described, the door and hopper have simultaneous angular movement so that the door is swung out of the way as the hopper is moved into charging position. In the modified form, the door only is mounted for swinging movement. In either case, means are provided whereby the desired angular movement may be easily effected by manual effort. On the other hand, the rectilinear movement of the hopper in both cases is effected by power means. In both forms of the invention, the construction is relatively simple, requiring little or no maintenance, and does not add materially to the cost of the mixer.

Although I have illustrated and described but two preferred embodiments of my invention, it will be recognized that changes in the details of construction disclosed may be made without departing from the spirit of the invention or the scope of the appended claims.

I claim:

1. A charging and discharging mechanism for

a mixer including a frame and a drum rotatable therein having an opening at one end, said mechanism comprising spaced supports extending from said frame adjacent said end, blocks slideable along said supports, a charging hopper disposed between said supports, shafts extending coaxially from said hopper and seated in said blocks, a closure for said end and means mounting said closure for swinging movement about the axis of said shafts.

2. A charging and discharging mechanism for a mixer as defined by claim 1 characterized by said closure being mounted on the hopper and said hopper rotating with the closure.

3. A charging and discharging mechanism for a mixer as defined by claim 1 characterized by said hopper being non-rotatable.

4. A charging and discharging mechanism for a mixer as defined by claim 1 characterized by means for actuating said blocks along said supports.

5. A charging and discharging mechanism for a mixer including a frame and a drum rotatable therein having an opening at one end, said mechanism comprising spaced supports extending from said frame adjacent said end, bearing blocks slideable along said supports, a charging hopper disposed between said supports, trunnions on said hopper journaled in said blocks and a closure for said end carried on said hopper.

6. A charging and discharging mechanism for a mixer including a frame and a drum rotatable therein having an opening at one end, said mechanism comprising spaced supports extending from said frame adjacent said end, blocks slideable along said supports, a charging hopper disposed between said supports, shafts extending coaxially from said hopper and seated in said blocks, a closure for said end, a yoke journaled on said shafts and a closure for said end mounted on said yoke.

7. A charging and discharging mechanism for a mixer as defined by claim 1 characterized by hydraulic motors on said supports for actuating said blocks.

LAWRENCE E. JOSEPH.
